UNITED STATES PATENT OFFICE.

PETER FULL, OF VERMILION, OHIO.

SCRAPING-TOOL.

1,082,802.

Specification of Letters Patent. Patented Dec. 30, 1913.

Application filed April 2, 1913. Serial No. 758,383.

To all whom it may concern:

Be it known that I, PETER FULL, a citizen of the United States, and a resident of Vermilion, county of Erie, and State of Ohio, have invented a new and useful Improvement in Scraping-Tools, of which the following is a specification, the principle of the invention being herein explained and the best mode in which I have contemplated 10 applying that principle, so as to distinguish it from other inventions.

The subject of the present application is a scraping tool designed for various uses, but with particular reference to the requirements which must be met in such tool if it is to be adapted for use in scraping the deposits from the hulls of boats. In such tools it is essential that a very secure grip of the scraping blade be had as the force which 20 must be applied to remove the deposits from the hulls is considerable and anything but a very secure grip will permit the scraping blade to be forced back onto the holder which will in time injure or split the handle 25 to which the holder is attached.

To the accomplishment of these and related ends said invention then consists of the means hereinafter fully described and particularly pointed out in the claims.

30 The annexed drawing and the following description set forth in detail certain mechanism embodying the invention, such disclosed means constituting, however, but one of various mechanical forms in which the 35 principle of the invention may be used.

In said annexed drawing:—Figure 1 is a perspective view of my invention; Fig. 2 is a section on the line 2—2 in Fig. 1; Fig. 3 is a section on the line 3—3 in Fig. 1; Fig. 4 is a longitudinal section on the line 4—4, Figs. 1 and 3 and Fig. 5 is a perspective view of a modified type of blade which may be used for some purposes.

The general appearance of the invention 45 is seen from Fig. 1, there being a suitable handle 1 to which is attached a holder 2 consisting of a flat plate provided with a plurality of laterally disposed shouldered lugs 3, there being preferably four of such lugs, 50 disposed as shown in Fig. 1. The scraping blade 4 is loosely and removably mounted between the lugs 3 and the holder 2, and the set screw 5 or other means is employed for retaining the blade in the holder. The 55 set screw 5 is disposed centrally in the holding member for the purpose of giving the

blade 4 a slightly arched form, as seen in Fig. 3 when the set screw is adjusted to hold the blade in the holder. The advantage of slightly arching the blade is that a 60 much better grip is secured than by merely pressing the blade against the lugs or against the holder, and this additional grip is required to maintain the blade in its proper relation to the holder in a tool of 65 this sort adapted to be used on hulls. As will be seen from Fig. 4 the blade is bowed longitudinally as well as transversely by the pressure of the set screw. Such pressure is absolutely necessary in such a tool 70 as mere frictional contact between the blade and the holder has proven to be insufficient to maintain the blade in position. By placing the set screw centrally of the lugs the blade is made to engage against both the 75 lugs and the holder as will be seen from Figs. 2 and 3. The blade is here shown to be engaged on either side against lug and plate and this "leverage" engagement as it may be termed is extremely secure. Additional 80 security is obtained from the longitudinal deflection of the blade which gives the same two point "leverage" engagement in that plane. This engagement is so secure that any pressure which the average 85 workman may put upon the tool is insufficient to cause slippage of the blade.

The blade 6 shown in Fig. 5 will preferably be used for horizontal surface work such as decks, etc., and will be held in engagement with the holder in the same manner as is the straight blade. I have shown the blades sharpened at either end to increase the use of each blade before resharpening but this may be done as individual users desire.

The simplicity and effectiveness of the present holding means adapt my scraping tool to rough work hulls of vessels and the like to which previous scraping tools have been totally inadequate.

Other modes of applying the principle of my invention may be explained instead of the one explained, change being made as regards the mechanism herein disclosed, provided the means stated by any of the following claims or the equivalent of such stated means be employed.

I therefore particularly point out and distinctly claim as my invention:

1. A scraper, comprising a suitable handle, a holder attached directly thereto and

- provided with a plurality of spaced pairs of laterally disposed shouldered lugs, a scraping member loosely received between said lugs and the body of said holder, and 5 fastening means mounted substantially centrally in said holder and independently of said handle, said means being adapted to force said member into resilient engagement with said lugs and said holder.
- 10 2. A scraper, comprising a suitable handle, a holder attached directly thereto and provided with a plurality of spaced pairs of laterally disposed shouldered lugs, a scrap-

ing member loosely and removably mounted between said lugs and the body of said holder, and a set screw adjustably mounted substantially centrally in said holder and independently of said handle, said set-screw being adapted to force said member into resilient engagement with said lugs and 15 said holder.

Signed by me, this 31 day of March, 1913.

PETER FULL.
